DESIGN FOR A DOLL OR SIMILAR ARTICLE

Ethel Rice, New York, N. Y.

Application February 21 1944, Serial No. 112,659

Term of patent 3½ years

(Cl. D34—4)

To all whom it may concern:

Be it known that I, Ethel Rice, a citizen of the United States of America, residing in New York city, county of New York, and State of New York, have invented a new, original, and ornamental Design for a Doll or Similar Article, of which the following is a specification, reference being had to the accompanying drawings, forming part thereof, wherein,

I claim:

The ornamental design for a doll or similar article, substantially as shown.

ETHEL RICE.
